UNITED STATES PATENT OFFICE.

JACOB LUNDGREN, OF PHILADELPHIA, PENNSYLVANIA, ASSIGNOR TO TINIUS OLSEN
TESTING MACHINE COMPANY, OF PHILADELPHIA, PENNSYLVANIA, A CORPOR-
ATION OF PENNSYLVANIA.

BALANCING MACHINE.

Application filed April 24, 1923. Serial No. 634,334.

This invention relates to devices for locating and correcting unbalance in bodies designed for rotation, and one object of the invention is to provide a simple, accurate and convenient machine of the type noted.

Another object of the invention is to provide a balancing machine by which it shall be possible not only to quickly locate the points on a rotary body at which balancing corrections should be made, but which shall be of such a nature as to give correct readings of the amounts of the corrections required.

I also desire to provide a machine whereby it shall be possible with two corrections to completely balance or completely correct the unbalance of a rotatable body.

These objects and other advantageous ends I attain as hereinafter set forth, reference being had to the accompanying drawings, in which,

Figs. 1 and 2 are respectively a side and an end elevation of a balancing machine constructed in accordance with my invention;

25 and,

Fig. 3 is a plan of the machine shown in Figs. 1 and 2.

In the above drawings, 1 represents a hollow base having two parallel, longitudinally extending guides in the form of rails or tracks 2-2. Slidably mounted on these tracks is a carriage 3 supporting a pair of transverse knife edges 4-4 and including longitudinally extending racks 5-5 respectively engaged by gears 6-6 fixed to a transverse shaft 7 journaled in the base 1. This shaft projects at one side of the frame where it is provided with a head 8 which permits of its convenient adjustment. Rotation of said head, through the gears 6 and the racks 5, will shift the carriage 3 and with it the two knife edges 4 longitudinally of the base 1.

Supported for the most part on the knife edges 4 is an elongated rectangular frame including two parallel side members 9-9 and two end members 10 and 11 connecting said side members, the under face of the side members 9 being flat adjacent and in engagement with the knife edges 4 to permit of a relative sliding adjustment of the latter. Projecting from the end member 10 is a bracket 12 perforated for the passage of a vertically extending bolt 13 whose lower

end is fixed in a bracket 14 mounted on the end of the base 1. Coaxial with this bolt are two springs 15 and 16, of which the first is confined between the brackets 12 and 14 and the second between the bracket 12 and a nut 17 adjustably mounted on the upper end of said bolt.

At the opposite end of the machine a pair of arms 18-18 projects from the member 11 and carries a plate 18^a perforated for the passage of a bolt 19 whose lower end is fixed to a bracket 20 mounted on the adjacent end of the base 1. Two springs 15^a and 16^a are confined on this bolt, the first between the bracket 20 and the plate 18^a and the second between said plate and a nut 21 adjustably threaded on said bolt. From the above description, it will be appreciated that the frame is carried upon the two knife edges 4-4 and is steadied at its ends by the two pairs of spring 15-16 and 15^a and 16^a.

To prevent movement of the frame 9-9-10-11 longitudinally of the base, I provide on one of the side members 9 an inwardly projecting arm 22 and mount a tie member 23 in the form of a flexible bar or ribbon so as to extend therefrom to an arm or bracket 24 on one end of the base. It is to be understood that this tie member 23 is flexible so as to permit of limited oscillatory movement of the frame 9-9-10-11 on its supporting knife edges.

In accordance with my invention, I mount on one end of oscillatory frame a transversely extending driving shaft 25, having splined to it a driving pulley 26 or other element designed to be actuated from a suitable source of power such as a motor (not shown) preferably mounted on said frame. Said shaft is longitudinally adjustable through its bearing and for this purpose is provided on one end with a collar 27 loose upon and confined between a milled head 28 and a suitable shoulder of said shaft. The collar 27 is provided with a projecting tooth 29 designed to coact with the teeth of a ratchet 30 fixed to and projecting from one of the side members 9 of the frame. By this means said shaft may be adjusted longitudinally of its bearings and maintained in any given position.

The shaft 25 has fixed to it a worm 31 meshing with a worm wheel 32 fixed to a shaft 33 journaled in suitable bearings so

as to be rotatably supported in one central longitudinal plane of the oscillatory frame. The forward end of this latter shaft is provided with a suitable chuck or coupling member 34 and is aligned with a pair of bearings 35 and 36 adjustably carried by the side members 9-9 of said frame. For this purpose said bearings are formed as part of bars or cross members 37 and 38 whose ends are slidably adjustable on the side members 9-9. Moreover, the adjacent ends of said cross bars are tied together by plates 39-39 each of which has one end fixed to a cross bar 38, for example, by suitable means such as a screw 40, while its opposite end is longitudinally slotted, as indicated at 41, for the reception of a second screw 42 whereby the second cross bar 37 may be clamped at any desired distance from the cross bar 38. The bearings 35 and 36 are designed to receive and rotatably support the object, such as a motor armature, which is to be balanced, and as above noted, are suitably aligned with the shaft 33 to permit of the latter being coupled to the shaft of said armature, by the member 34.

Also carried by the oscillatory frame 9-9-10-11, parallel with and immediately below the shaft 25, is a second transverse shaft 43 having fixed thereon a gear 44 meshing with a second gear 45 splined to the driving shaft 25. This second shaft 43 has fixed to it a worm 46 meshing with the worm wheel 47 fixed to a shaft 48 extending longitudinally of the oscillatory frame and carried in suitable bearings so as to lie in the central vertical plane including the center line of the shaft 33. This second longitudinal shaft carries a pair of oppositely projecting counterbalance weights 49 and 50, which are rotatably fixed to it so as to project therefrom in opposite lines, although the former weight is connected to or is formed as part of a collar 51 whereby it may be moved longitudinally of its shaft toward and from said other weight 50. These weights are of such design and construction that when in one adjusted position they are balanced so that they with the shaft may be rotated without causing gyroscopic stresses in said shaft and in the structures connected thereto. When, however, the weight 49 is moved longitudinally of the shaft away from the weight 50, the resulting unbalance sets up gyroscopic forces whose magnitude is proportional to the speed of rotation and to the distance between the weights.

For the purpose of adjusting the relative positions of the weights 49 and 50, I journal a short shaft 52 in suitable bearings carried by one of the frame members 9 and mount on the inner end of said shaft a gear 53 meshing with a rack 54 extending longitudinally of said frame carrying an arm 51^a engaging the collar 51 of the weight 49.

The outer end of said shaft 52 is provided with an indicating dial 55 and a milled head 56 to permit of its being conveniently turned, and I also provide a pointer or indicator 57 on the side frame member 9 in position to cooperate with the graduations of said dial. The latter is designed to give a zero reading when the weights 49-50 lie with their centers of gravity in the same plane at right angles to the shaft 48 and said dial is graduated in any convenient units such as inch-ounces or foot-pounds.

For indicating the presence and magnitude of oscillatory movement of the frame 9-9-10-11, I provide a vertically extending standard 60 projecting upwardly from the base 1 at one side thereof and on its upper end mount a graduated indicating dial 61. On the adjacent side member 9 of the frame, I also provide an upwardly extending arm 62 placed to extend vertically to one side of the median transverse plane of said frame and through suitable mechanism connect the upper end of this arm 62 with a pointer 63 journaled concentrically of the dial 61, the arrangement being such that an oscillatory movement of the arm 62 will cause a proportional oscillatory movement of said pointer.

With the above described arrangement of parts, the bearings 35 and 36 are adjusted to suitably receive and support the armature or other object α whose balance it is desired to correct, and the shaft of this object is coupled to the member 34 of the shaft 33. The head or handle 8 of the shaft 7 is now turned to set the knife edges 4 in a vertical plane intersecting some part of the rotating body α in which balancing corrections may conveniently be made, after which the machine may be put in operation by rotating the shaft 25 at a suitable speed. The body α will now be rotated in the bearings 35 and 36 and the shaft 48 with the weights 49 and 50 will likewise be rotated at the same speed. Unless the rotating body is in perfect balance, this rotation will cause the frame 9-9-10-11 and hence the pointer 63 attached thereto to vibrate, and by means of the head 56, the counterbalancing weights 49 and 50 may be moved apart or may be adjusted relatively to each other until this vibration ceases or becomes a minimum. By longitudinally adjusting the shaft 25, the shaft 33 may then be turned to adjust the angular relation of the rotary body to the counter-balancing weights 49 and 50, and this will usually again cause a resulting vibration of the oscillatory frame as shown by the oscillation of the pointer 63. By means of further adjustment of the counter-balancing weights by turning the head 56, this vibration as before may be stopped or reduced to a minimum.

A reading may now be taken of the ad-

justment of the weights 49 and 50 as shown by the graduated dial 55 relatively to the pointer 57, and correction of the unbalance so determined is made on the rotating body α in some convenient plane at right angles to its axis of rotation into which the knife edges 4-4 will subsequently be brought. As before indicated, the dial 55 is graduated in such units that the reading indicated by the pointer 57 will give the amount of the required correction. In order that this correction may be made at the proper point of the periphery or in the proper plane of the body α , the shaft 25 is rotated by hand until the two counterweights 49 and 50 are in the vertical plane of the shaft 48. If the counterweight 50 nearest the object α is now the upper of the two weights, said object will be corrected for unbalance if material be added to its uppermost portion by the amount and at the distance from the plane of the knife edges indicated by the reading of the dial 55.

The carriage 3 is now adjusted by rotating the head 8 until the vertical plane of the knife edges 4-4 is made coincident with the plane in which correction has been or should be made on the body α . The machine is now again put in operation and if as is usually the case, unbalance is indicated by vibration of the oscillatory frame 9-9-10-11 on the knife edges 4-4 as previously explained, this is again brought to zero or reduced to a minimum by adjusting the distance between the counterweights 49-50 by rotation of the head 56. Thereafter as above explained, the angular relation of the two counterweights and the rotating body α is adjusted by longitudinal adjustment of the shaft 25 and any resulting vibration of the frame is again reduced to zero by further adjustment of the head 56. The reading of the dial 55 will now indicate in inch-ounces or other convenient unit the amount of the correction to be made to the rotating body. This correction is to be made at a point on the body α in the vertical plane originally defined by the knife edges 4-4 and positioned at this point on the periphery of the body determined as above explained.

As a result of the above operations, it will be found that the body α is in complete static as well as in complete dynamic balance and it will be appreciated that the balancing operation may be quickly and conveniently accomplished and that with the highest degree of accuracy.

It is to be noted that it is not necessary to correct the unbalance until both readings have been taken as described above.

I claim:

1. The combination in a balancing machine of a supporting structure providing a movable fulcrum; an oscillatory frame

mounted on said structure; adjustable counterbalance weights on the frame; means also on the frame for supporting a body to be balanced; means for simultaneously rotating said body and the counterbalance weights; with means including a longitudinally adjustable shaft for varying the angular relation of said weights and the body to be balanced.

2. The combination of a bodily movable knife edge supporting member; a frame fulcrumed on said member and having means for rotatably supporting a body to be balanced; a device also carried by the frame for determining the amount of unbalance of said body for different positions of said member, said device including a pair of adjustable counterbalancing weights; means for adjusting the distance between said weights; and means including a bodily movable shaft for adjusting the angular relation of the counterweights and the rotating body.

3. The combination in a balancing machine of a supporting structure providing a bodily movable fulcrum; an oscillatory frame mounted on said structure; two shafts rotatably carried by said frame; means for rotating said shafts including an axially movable shaft for adjusting the angular relation between said first-mentioned shaft; counterbalance weights actuated by one of said shafts; bearings on the frame for rotatably supporting a body to be balanced in line with and coupled to the second shaft; means for adjusting the counterweights toward and from each other; and means for indicating the oscillation of said frame for different positions of said movable fulcrum.

4. The combination in a balancing machine of a single fulcrum structure; an oscillatory frame mounted thereon; springs engaging the opposite ends of said frame for rotatably supporting a body to be balanced; counterbalance weights also carried by the frame; means including a pair of shafts for synchronously rotating said weights and body in said bearings; means for adjusting the distance between the counterweights to reduce the oscillation of the frame due to unbalance of the body carried thereby when the latter is rotated; a device connected with said last means for indicating the amount of correction to be made in said body; one of said shafts being longitudinally movable to vary the angular relation of the body to be balanced and the counterbalance weights.

5. The combination in a balancing machine of a supporting structure; a pair of knife edges slidably mounted on said structure; means for sliding said knife edges on the structure from one desired position to another; a frame fulcrumed on the knife edges; longitudinally extending means for preventing longitudinal movement of said frame while permitting its oscillation; coun-

- terbalancing weights carried by the frame; means for simultaneously rotating said weights and a body to be balanced; and means for determining the amount of unbalance of said body when it is rotated with said knife edges successively in said desired positions.
6. A balancing machine comprising a frame for supporting a body to be tested; counterbalancing means; a pair of parallel shafts mounted on said frame and respectively associated with said body and said counterweights, said shafts being formed to constitute elements of worm-and-wheel gearing, one of said shafts being movable longitudinally of the other, whereby the angular position of said body and said counterbalancing means may be varied; and means for operatively associating said shafts, whereby both shafts may be simultaneously actuated.
7. A balancing machine comprising a supporting structure; a movable fulcrum member; a frame mounted for oscillatory movement thereon; longitudinally extending means for preventing a longitudinal movement of the frame while permitting its oscillation; and a pair of connected shafts, one of said shafts being so mounted as to be adjustable longitudinally of the other, whereby the angular relation between said shafts may be varied.
8. A balancing machine comprising a frame for supporting a body to be tested; counterbalancing means; and a pair of connected shafts mounted on said frame and respectively associated with said counterweights and said body, the latter shaft being longitudinally adjustable, whereby the angular relation between said body and said counterbalancing means may be varied.
9. A balancing machine comprising a frame for supporting a body to be tested; counterbalancing means; a pair of connected shafts mounted on said frame and respectively associated with said counterweights and said body, the latter shaft being longitudinally adjustable, whereby the angular relation between the body and said counterbalancing means may be varied; and locking means for said longitudinally movable shaft.
10. A balancing machine comprising an oscillatory frame providing a mounting for a body to be tested and also for counterbalancing weights; and a pair of connected shafts respectively associated with said weights and said body, the latter shaft constituting a driving shaft and so mounted as to be movable longitudinally independently of the other shaft, whereby the angular relation between said body and said counterweights may be varied.
11. A balancing machine comprising a frame for supporting a body to be tested; counterbalancing means; a pair of shafts; and means for connecting the same, said shafts being respectively associated with said body and said counterweights and formed to constitute elements of worm-and-wheel mechanism, one of the shafts being axially movable so as to vary the angular position between said body and said counterbalancing means.
12. In combination, supporting means for a body to be tested; counterbalancing means; an axially movable driving shaft for said body mounted on said supporting means and provided with a worm; means for locking said shaft in any one of a number of positions; and a shaft for actuating said counterbalancing means adapted to be driven by said axially movable shaft and provided with a worm.
13. A balancing machine including an oscillatory frame, and a pair of connected shafts carried thereby, said shafts being formed to constitute elements of worm-and-wheel gearing, one of said shafts being so mounted as to be adjustable longitudinally of the other, whereby the angular relation of said shafts may be varied.
14. A balancing machine comprising an oscillatory frame adapted to provide a mounting for a body to be tested; said frame also providing a mounting for counterbalancing weights, a pair of connected shafts for respectively actuating said body and said weights, said shafts being formed to constitute elements of worm-and-wheel gearing, one of said shafts being adjustable longitudinally of the other, whereby the angular relation of said body and said counterweights may be varied, and means for locking said longitudinally movable shaft.
15. A balancing machine comprising an oscillatory frame adapted to provide a mounting for a body to be tested, said frame also providing a mounting for counterbalancing weights, a pair of connected shafts for respectively actuating said body and said weights, said shafts being formed to constitute elements of worm-and-wheel gearing, one of said shafts being adjustable longitudinally of the other, whereby angular relation of said body and said counterweights may be varied; and ratchet mechanism for adjustably securing said longitudinally movable shaft in a desired position.
16. Means for balancing a rotating body including, a supporting fulcrum, means for bodily moving said fulcrum from one desired position to another, counterbalancing means, a driving shaft, and means for axially adjusting the driving shaft to vary the angular relation between said body and said counterbalancing means.

JACOB LUNDGREN
